UNITED STATES PATENT OFFICE.

FRANK R. BATCHELDER, OF WORCESTER, MASSACHUSETTS, ASSIGNOR TO MILLS BELT COMPANY, OF WORCESTER, MASSACHUSETTS, A CORPORATION OF MASSACHUSETTS.

WOVEN CARRIER EQUIPMENT.

1,392,551.

Specification of Letters Patent.

Patented Oct. 4, 1921.

Application filed January 22, 1920. Serial No. 353,318.

To all whom it may concern:

Be it known that I, FRANK R. BATCHELDER, a citizen of the United States, residing at Worcester, in the county of Worcester, State of Massachusetts, have invented 5 a certain new and useful Improvement in Woven Carrier Equipment, of which the following is a specification, reference being had therein to the accompanying drawings.

10 The invention relates to woven pocketed carrier-equipment of the general class including cartridge carriers and constructionally similar equipment for military and other uses. More particularly, it relates to 15 what for convenience may be termed accessory pocket equipment. By accessory pocket equipment I intend carriers or pockets such as for use are mounted detachably upon a supporting belt or the like, or upon another 20 carrier forming a part of belt-like equipment. These generally consist of what for convenience may be termed a pocket-piece, a cover or flap for the opening or mouth of the pocket, and a supporting-loop adapted 25 to embrace the belt or carrier to which the accessory carrier or pocket is applied.

The first part of the invention provides in 30 improved manner for combining the supporting-loop and cover or flap of an accessory carrier or pocket with the pocket-piece of the latter, and for finishing off the carrier or pocket at the bottom of the pouch thereof.

The second part of the invention provides 35 an improved edge-binding and backing for the pocket-piece.

The features of the invention will be described first with reference to the illustrated embodiments thereof, and then will be more particularly pointed out in the claims at the 40 close of this specification.

In the drawings,—

Figure 1 shows a cartridge belt of a well-known type having applied thereto a series of accessory pockets embodying the features 45 of the invention.

Fig. 2 is a view on a relatively enlarged scale, partly in section on line 2—2 of Fig. 1.

Fig. 3 is an isometric view of an accessory carrier or pocket embodying the features of 50 the invention.

Fig. 4 is a view in horizontal section in the plane of line 4—4 of Fig. 3.

Fig. 5 is a view in vertical section in the plane of line 5—5 of Fig. 3.

55 Figs. 6, 7 and 8 are views in vertical sec-

tion illustrating modifications in the connection of the loop and cover or flap with the top margin of the pocket-piece.

Fig. 9 is an isometric view showing a modification in the construction at the bottom of the pocket.

Having reference to the drawings,—

The cartridge belt shown in Fig. 1, a portion thereof being shown in Fig. 2, is of the usual construction comprising opposite 65 pocketed carriers 1, 2, and an adjustment strap 3 at the rear, the front ends of the carriers 1, 2, being furnished as usual with interengaging fastener-members 4, 5, for holding the belt in place encircling the waist 70 of the wearer. Each of the said carriers 1 and 2 is provided with a series of pockets 6, 6, to contain cartridges 7, 7, held by clips 8.

Fig. 1 shows in connection with the carrier 2 three accessory pockets 9, 9, 9, which are supported upon the said carrier by means of their suspensory loops 10, 10, 10, encircling the carrier 2, as shown also in Fig. 2. As thus combined with the carrier 80 2, the pockets 9, 9, are supported in place at the front of the usual pockets 6, 6, and lie against the outer faces of the latter. In this instance, the accessory pockets 9, 9, are intended to be occupied by loaded magazines 85 11, 11, of the kind used in automatic rifles. Such magazines 11, 11, are represented as arranged in pairs in vertical position within the pockets 9, 9. The said pockets are larger and deeper than the pockets of the carrier 2, 90 as necessitated by the size of the magazines. On account of the length of the magazines, the lower portions of pockets 9, 9, extend down below the carrier 2, as shown. The said pockets 9, 9, are provided with flexible 95 covers or flaps 12, 12, resembling the covers or flaps 13, 13, of the pockets 6, 6, and, like the latter, furnished with fastener-devices 14, 14, of "glove-fastener" type, to secure them in closed-down condition.

Individual accessory pockets such as thus far described, may be supplied to an infantry-man equipped with the regular equipment, including a regular cartridge-belt like that shown in Fig. 1, so that, after filling the 105 regular pockets of said cartridge-belt with cartridges held by regular rifle clips, he may combine with the said cartridge-belt in the manner shown in Figs. 1 and 2 accessory pockets containing automatic rifle magazines 110

loaded with cartridges. The cartridges themselves are the same in both cases. This will enable him, after firing the cartridges contained in the automatic rifle magazines, to take the loaded clips from the regular pockets of his cartridge-belt and transfer the cartridges therefrom to the automatic rifle magazines.

The cartridge-belt shown in the drawings is, as preferred in practice, composed of woven material, with the pockets formed upon the respective carriers 1 and 2 in the process of weaving, in manner well-known in the art. The accessory pockets, also, are of woven material, each thereof comprising, essentially, a pocket-piece composed of a back-web 9^a and an outstanding pocket-pouch woven thereon, and an applied loop 10 and cover or flap 12.

Referring now to the features of my invention:—

By one feature of the first part of my invention I combine the lower end of the strip of material of which the loop 10 is composed with the bottom margin of the pocket-piece in a manner securing a number of good results. The preferred construction is illustrated most clearly in Figs. 3, 5, and 6. In said figures, the pocket-piece is formed with a split or divided bottom marginal portion 9^c. The lower end-portion 10^c of the strip bends around the edge of the rear wall of said split or divided portion 9^c and is entered between the two walls of the latter. Fastenings 15, 15, preferably transverse lines of stitches, engage with the two walls of the split or divided marginal portion, as well as with the upturned end of the strip of which the loop is formed, and with the portion of the said strip which extends upward at the back of the said marginal portion, and also with the lower portion of the lining or backing piece 20 to which reference is made hereinafter, when said piece 20 is employed. The bend or turn of the strip at 10^c by inclosing the edge of the rear wall of the split or divided marginal portion, as well as the lower margin of the said lining or backing piece, covers, protects, and conceals the said edge and lower margin, and affords a smooth round finish for the bottom portion of the accessory carrier or pocket. The extremity of the strip of which the loop 10 is formed is concealed and protected between the walls of the divided bottom margin, and a very secure attachment of the said end is effected. The finish and protection furnished by forming the lower portion of the loop-strip into a bend 10^d inclosing a bottom marginal portion of the accessory carrier or pocket is of importance, because it reduces the wear of those portions of the soldier's uniform with which the lower part of the accessory carrier or pocket comes in contact below the regular cartridge-

belt. There are no exposed marginal edges, folds, or seams, at the back of the lower portion of the accessory carrier or pocket to cause wear or to catch upon adjacent portions of equipment. For convenience in applying the stitches or other fastenings 15, 15, the divided bottom margin of the pocket-piece projects below the bottom of the pouch. Two transverse lines of stitches are represented in the drawings. In some instances, as illustrated in Fig. 9, Sheet 2, the extremity of the strip of which loop 10 is formed may be carried up at the front face of the projecting bottom marginal portion and secured against the said face by the fastenings 15, 15. In such instances the said marginal portion will not be of the divided construction that has been described.

At the top of the pocket-piece the strip composing the loop 10 is attached to the pocket-piece, preferably by having the attaching portion of the said strip inserted between the two walls of a divided top marginal portion 9^d of the pocket-piece, and securing it therein by means of stitches or other applied fastenings 16, 16, passing through the two walls of said marginal portion and the interposed attaching portion of the strip. In each of Figs. 5 and 6 the attaching portion of the cover or flap 12 also is entered between the said walls of the divided top marginal portion of the pocket-piece, and is secured by the said fastenings 16, 16. In the construction shown in Fig. 5, the loop 10 and cover or flap 12 are continuous with each other, that is to say, they are constituted by different portions of the length of one continuous strip, the attachment to the top margin of the pocket-piece being effected by folding the continuous strip upon itself and tucking the fold into the opening in the divided top margin. In Fig. 6, the loop 10^d and cover or flap 12^d, instead of being continuous with each other, are composed of separate pieces of strip material having their attaching end-portions inserted together within the opening of the divided top margin of the pocket-piece, and secured by the fastenings 16, 16.

In the construction shown by Fig. 7, the loop, 10^e, and cover or flap, 12^e, are portions of one continuous strip as in Fig. 5, but the top marginal portion 9^e of the pocket-piece is undivided. At the upper end of the loop the strip is secured or fastened at the back of the top marginal portion 9^e, by means of stitches or other fastenings 16, 16, and the continuation of the strip which forms the cover or flap 12^e bends forward over the top of the said top margin in closing or covering the pocket. In Fig. 8 the construction shown in Fig. 7 is modified by carrying the strip down in front at the top margin of the pocket-piece and fastening it there, so that a bend of the strip incloses the said top

margin, the stitches or other fastenings 16, 16, being in engagement with the strip at both the front and the rear of the top margin of the pocket-piece.

5 The constructions which have been described with reference to Figs. 5, 6, 7, 8, provide in a desirable manner for effectively attaching the loop and cover or flap to the pocket-piece. The described mode of attachment of the lower end of the loop to the bottom margin of the pocket-piece lessens very materially the liability of such end to rip or break loose. The lower extremity of the strip itself, in addition to being concealed and protected, is held better than it could be if it lay exposed on the back surface of the pocket-piece. Various practical advantages in the process of manufacture are secured.

20 Referring to the second part of the invention, namely the improved edge-binding and backing for the pocket-piece,—

In the process of manufacture usually followed in practice, the pocket-pieces for a number of accessory carriers or pockets usually are woven side by side in a series as portions of a continuous pocketed web. After the weaving has been accomplished, the respective pockets are separated from one another by cutting transversely across the sections of web between one pocket and the next. This procedure produces a corresponding number of separate pocket-pieces, each having portions 9^b, 9^b, (Fig. 4) of the said web-sections projecting in the form of flanges or fins at opposite sides of its pocket, the said projecting flanges or fins constituting side marginal portions of the pocket-piece. These flanges or fins are trimmed away more or less closely to the sides of the pocket; but are left with cut or raw, *i. e.*, unfinished edges, and of course such edges would tend to fray and ravel if left unprotected and exposed. The 45 second part of the invention has for its object to effect the binding and finishing of the projecting flanges or fins 9^b, 9^b, and in addition provide the pocket-piece with a smooth lining or backing 20 free from 50 prominent ridges constituted by projecting seams, folds, or edges of a character liable to catch against portions of the supporting belt or carrier in slipping the accessory carrier or pocket upon said belt or carrier, or 55 in adjusting it thereon, or in slipping it therefrom.

The lining or backing-piece 20 lies against the rear face of the pocket-piece, as indicated in Figs. 4, 5, etc. Its lateral margins 60 are doubled back upon themselves to conceal their edges, as shown in Figs. 3, 4 and 9. The doubled portions are folded around the flanges or fins 9^b, 9^b, of the pocket-piece, as in the said figures, so as to inclose the said 65 flanges or fins, and are secured to the latter

by means of applied fastenings 22, preferably stitches, passing through all the thicknesses adjacent the sides of the pockets. The top and bottom marginal portions of the lining or backing-piece 20, usually 70 turned back upon themselves as in Figs. 5, 6, etc., to conceal the edges thereof, are caught by the transverse lines of fastenings 15, 15, and 16, 16, and thereby secured. At the bottom of the pocket-piece, the lower marginal portion of the lining or backing-piece 75 is contained within the bend 10^a of the lower end-portion of the loop-strip, and confined between the said strip and the bottom marginal portion of the pocket-piece. 80

What is claimed as the invention is:—

1. In pocketed carrier equipment, an accessory carrier or pocket comprising a pocket-piece having a pocket thereon, and a suspensory loop at the back of said pocket-piece, said loop composed of a strip of web material fastened to the top of the pocket-piece by a transverse line of fastenings, with the lower end-portion of said strip bent around and up in front of a bottom marginal 90 portion of the pocket-piece, so as to form a bend inclosing said marginal portion and furnish a smooth rounded finish to the bottom of the pocket-piece, and fastenings securing together said lower end-portion and 95 said bottom marginal portion.

2. In pocketed carrier equipment, an accessory carrier or pocket comprising a pocket-piece having a pocket thereon and also formed with a divided bottom margin, 100 and a suspensory loop at the back of said pocket-piece, said loop composed of a strip of web material fastened to the top of the pocket-piece by a transverse line of fastenings, with the lower end-portion of said strip bent around the rear wall of said divided bottom margin and up between the two walls of the latter, in a bend inclosing the said rear wall and furnishing a smooth rounded finish to the bottom of the pocket-piece, and fastening securing together the 105 said lower end-portion and the walls of the divided bottom margin.

3. In pocketed carrier equipment, an accessory carrier or pocket comprising a 115 pocket-piece having a pocket thereon and also formed with a divided top margin, and a suspensory loop at the back of said pocket-piece having a portion of its material seated in the opening of said divided top margin 120 and secured therein by fastenings engaging with such end and the walls between which it is entered, and also having its lower end bent around and up in front of a bottom marginal portion of the pocket-piece so as 125 to form a bend inclosing said marginal portion and furnish a smooth rounded finish to the bottom of the pocket-piece, and fastenings securing together said lower end-portion and said marginal bottom portion. 130

4. In pocketed carrier equipment, an accessory carrier or pocket comprising a pocket-piece having a pocket thereon and also formed with divided top and bottom margins, and a suspensory loop at the back of said pocket-piece composed of a strip of web material having a portion of its material seated in the opening of the divided top margin and secured therein by fastenings engaging with such end and the walls between which it is entered, and also having its lower end-portion bent around the rear wall of the divided bottom margin and up between the two walls of the latter, in a bend inclosing the said rear wall and furnishing a smooth rounded finish to the bottom of the pocket-piece, and fastenings securing together the said lower end-portion and the walls of the divided bottom margin.
- 10 5. In pocketed carrier equipment, an accessory carrier or pocket, comprising a pocket-piece having a pocket thereon and also formed with a divided top margin, a suspensory loop at the back of said pocket-piece having its lower end attached to the pocket-piece and a portion of its material seated in the opening of said divided top margin, a pocket-cover or flap extending forward from within said opening, and fastenings securing together the walls of the divided top margin and the inserted portions of the loop and cover or flap.
- 15 6. In pocketed carrier equipment, an accessory carrier or pocket comprising a pocket-piece having a pocket thereon and formed with a divided top margin, and a strip or band of web material having one portion thereof formed into a cover or flap for the pocket, another portion formed into a suspensory loop at the back, and an intermediate portion tucked in and fastened between the walls of said divided top margin.
- 20 7. In pocketed carrier equipment, an accessory carrier or pocket comprising a pocket-piece having a pocket thereon and formed with divided top and bottom margins, and a strip or band of web material having one portion thereof formed into a pocket-cover or flap, another portion formed

into a suspensory loop at the back, an intermediate portion tucked in and fastened between the walls of the divided top margin, and the lower end of the loop bent around the edge of one wall of the divided bottom margin and fastened between the two walls of the latter.

50 8. A carrier or pocket comprising a pocket-piece woven with a pocket and having projecting flanges or fins at opposite sides of said pocket, and a lining or backing for said pocket-piece extending from side to side across the back of the latter and having its side-margins bent around the said flanges or fins to the faces thereof and secured by fastenings.

60 9. A carrier or pocket comprising a pocket-piece, a suspensory loop extending vertically at the rear thereof, said pocket-piece woven with a pocket and having projecting flanges or fins at opposite sides of the pocket, and a lining or backing at the surface of said pocket-piece next said loop, extending from side to side across said surface and having its side-margins bent around the said flanges or fins to the front faces thereof and secured by fastenings.

70 10. In pocketed carrier equipment, an accessory carrier or pocket comprising a pocket-piece having a pocket thereon and formed with a divided top margin, and a strip or band of web material having one portion thereof formed into a pocket-cover or flap, another portion formed into a suspensory loop at the back, and an intermediate portion tucked in and fastened between the walls of the divided top margin, and with its end at the lower end of the loop bent around the edge of a bottom marginal portion of the pocket-piece, up in front of such marginal portion, and secured by fastenings passing through the said end and said portion.

80 In testimony whereof I affix my signature in presence of two witnesses.

FRANK R. BATCHELDER.
